FIG. 1 is a front-top perspective view of a base part for electronic vaping device;

FIG. 2 is a front view of the base part for electronic vaping device shown in FIG. 1;

FIG. 3 is a rear view of the base part for electronic vaping device shown in FIG. 1;

FIG. 4 is a left side view of the base part for electronic vaping device shown in FIG. 1;

FIG. 5 is a right side view of the base part for electronic vaping device shown in FIG. 1;

FIG. 6 is a top view of the base part for electronic vaping device shown in FIG. 1;

FIG. 7 is a bottom view of the base part for electronic vaping device shown in FIG. 1; and,

FIG. 8 is a rear-bottom perspective view of the base part for electronic vaping device shown in FIG. 1.

The evenly spaced broken lines in the drawings depict portions of the base part for electronic vaping device that form no part of the claimed design. The dash-dot-dash lines represent a boundary of the claimed design.
